FRACTURE AND ORTHOPEDIC OPERATING
MACHINEHerbert M. Bergamini, New York, N. Y., assignor
of one-half to Albert Stephenson, New York,
N. Y.

Application March 21, 1935, Serial No. 12,244

12 Claims. (Cl. 128—84)

This invention relates to a fracture and orthopedic operating frame. It is particularly concerned with an apparatus of the above mentioned character which has for its object the support 5 of a patient in a fixed position for reduction and manipulation of skeletal injuries such as fractures or dislocations.

A feature of the present invention is that it eliminates the necessity of lifting the patient 10 from a stretcher or stretcher cart onto the operating apparatus or an operating table.

It is a further feature of the present invention that the patient is supported from above so that the space below the patient is free of obstructions 15 so that X-ray apparatus for either X-ray pictures or fluoroscopic examination of the injured part may be conveniently used while the patient is in position on the operating apparatus.

It is a further feature of the invention that 20 the apparatus embodying the invention affords accessibility to the patient for the application of plaster casings, molded plaster splints, or plaster casts, for retention of the reduced deformity. The apparatus of the present invention, 25 moreover, permits of the application of exact mechanical traction to displaced or over-riding fractures.

In the drawings forming part of this specification,

30 Figure 1 is a perspective view of an operating frame embodying features of the invention;

Figure 2 is a fragmentary view in sectional elevation;

35 Figure 3 is a fragmentary sectional view taken upon the section line 3, 3 of Figure 2 looking in the direction of the arrows.

Figure 4 is a fragmentary, detail sectional view of a clamp employed in a part of the apparatus;

40 Figure 5 is a sectional, detail view illustrating the mounting of one of the stirrups employed.

The frame is composed of pieces of pipe or tubing connected by ordinary fittings and joints, and comprises uprights 1, cross rails 2, and longitudinal track rails 3, upon which a carriage 4 is slidingly mounted. The carriage comprises transverse rails 5 having T couplings 6 on their ends which embrace the track rails 3 with capacity for sliding upon such track rails. The carriage also comprises a housing 7 having a top plate 8 affixed to the rails 5. A perineal bar 9 is supported by the carriage 4 and extends vertically downward therefrom. At the lower end of the perineal bar 9 provision is made of a small 50 sacral rest 10 adapted to be used for infants, and a larger sacral rest 11 adapted to be used for adults. The sacral rest 11 may be slid upward along the perineal bar and engaged in a spring clip 12 mounted on the carriage 4, to be held 55 out of the way when the rest 10 is to be used.

Normally, however, the rest 11 bears upon the rest 10 at the lower end of the bar 9.

Provision is made for adjusting the perineal bar vertically to raise or lower the sacral rest, and of means for adjusting the carriage longitudinally of the frame to shift the perineal bar and the sacral rest horizontally.

For adjusting the perineal bar vertically, provision is made of a rack 13 fixed on the bar and a pinion 14 for engaging and driving the rack. 10 The pinion 14 is fast upon a shaft 15 which is journaled in the housing 7 of the carriage 4. The shaft 15 also has fast upon it a worm wheel 16 which is driven by a worm 17 journalled in brackets 18 which are carried by the housing 7. 15 The worm shaft extends vertically and is provided at its lower exposed end with an operating wheel 19. Rotation of the wheel 19 turns the worm 17 and serves thereby to drive the perineal bar upward or downward, as desired, through the 20 worm wheel 16 and the pinion 14. The mechanism is automatically locked and retained in any position to which it may be adjusted, since the worm is of too slight pitch to be driven by the worm wheel 16.

25

Longitudinal adjustment of the carriage is effected through a long screw 20 which is supported by a frame cross bar 21. The screw 20 has collars 22 and 23 fixed upon it on opposite sides of the cross bar 21 for restraining the screw against 30 longitudinal movement. The screw is threaded through a bracket 24 fixed on the housing 7 and is provided with an operating wheel or handle 25. Rotation of the wheel 25 in one direction serves to propel the carriage 4 with the depending 35 perineal bar and sacral rest away from the operator, and rotation of the wheel in the opposite direction serves to propel the carriage and the depending parts toward the operator.

When a patient is to be operated upon for an 40 injury such as a leg fracture, he is supported on the sacral rest and caused to straddle the perineal bar. The foot of his injured leg is then secured in one of the stirrup members 26 and the injured leg is then stretched, by manipulation of the 45 stirrup to permit the bone to be set. The stirrups are duplicates of one another and a description of one will suffice for both.

The stirrups are carried upon a cross bar 27 which is supported on brackets 28 mounted on 50 the uprights 1, at the end of the frame. The cross bar 27 has rectangular end portions which fit in sleeves of the brackets 28 to restrain the cross bar against rotation. Each bracket 28 comprises a split ring portion 29 for encircling the 55 associated upright 1, and the halves of the split ring portion 29 are provided with jaws 30 which are adapted to be drawn together by a screw 31. The screw 31 is passed freely through one of the jaws and threaded into the other. It is provided 60

with an operating handle 32. The elevation of the bar 27 may be readily adjusted by releasing the clamping jaws of both brackets 28, shifting the bar up or down, and then tightening the 5 clamping jaws of the brackets.

Each stirrup comprises a foot receiving portion 33 which is pivotally connected through a T member 34 with a threaded stem 35. The threaded stem 35 extends freely through a sleeve 36 and is threaded through a nut 37 which abuts the outer end of the sleeve. The nut is provided with a hand wheel 38 which may be turned. A key 58, fast in the sleeve, enters a groove 59 in the rod, and prevents relative rotation of the 10 rod in the sleeve, which might be injurious to a patient's limb. Since the nut abuts the sleeve 36 it is held against movement toward the patient, and consequently rotation of the wheel 38 in a 15 clockwise direction as reviewed in Figure 1 is effective to draw the stirrup forcibly away from the 20 sacral rest and the operating bar.

The stirrup-carrying sleeve 36 is mounted in a split ring 39 having clamping jaws 40 extending from the two halves thereof. A screw 41 extends 25 freely through one of the clamping jaws and is threaded into the other. The screw 41 is provided with an operating handle 42 for increasing or relieving the clamping pressure. When the clamping pressure is relieved the sleeve may 30 be slid freely through the split ring member 39 and clamped in a new adjusted position. When the apparatus is being used to put traction upon an injured patient, however, the sleeve is clamped in fixed position and the traction is exerted 35 through rotation of the hand wheel 38.

The split ring 39 has a body portion provided with a flat lower face which rests upon an ear 43 of a supporting bracket 44. The split ring 39 also has a downwardly extending threaded stem 45 which passes through the ear 43. A sleeve 46 is threaded on to the stem 45. The sleeve 46 is provided with a hand wheel 47 whereby the sleeve may be turned to clamp the split ring 39 firmly to the ear 43. When the sleeve 46 is backed off the split ring 39 may be rotated about a vertical 45 axis to change the angular disposition of the stirrups relative to the sacral rest. This adjustment may be fixed by again tightening the sleeve to bind the parts in place.

The supporting bracket 44 includes a split ring portion 48 which encircles the bar 27. The two halves of this split ring are provided with jaws 49. A screw 50 is passed freely through one of the jaws and threaded into the other, and is provided with an operating handle 51 whereby the ears may be drawn forcibly together. When the jaws 49 are permitted to move apart the grip upon the bar 27 is relaxed and the entire stirrup structure may be adjusted either laterally of the 55 frame or angularly about the axis of the bar 27. The adjustment may be maintained by again turning the handle 51 to tighten the grip of the split ring 44 upon the bar 27.

It is generally desirable to support the patient's 65 injured leg in a sling while it is being operated upon. For this purpose provision is made of spring supporting hooks 52. The hooks are carried by sleeves 53 which are jointly mounted upon rods 54 and adapted to be fixed in adjusted position by means of set screws 55. The rods 54 are 70 loosely, pivotally mounted upon the shanks of threaded members 56 carried on opposite sides of the housing 7. The rods are capable of limited universal adjustment relative to the housing 7. A notched cross bar 57 is supported by the up-

rights 1 and the free ends of the rods 54 are adapted to be set in a variety of positions simply by shifting them from one notch to another of the cross bar 57.

In using the operating frame of the present 5 invention in the reduction and manipulation of skeletal injuries such as fractures or dislocations of the lower extremities, the patient is placed in position for the operation by rolling the stretcher cart on which he lies directly under 10 the operating frame. The sacral rest is then lowered by manipulation of the hand wheel 19 and moved longitudinally of the frame by manipulation of the hand wheel 25 until it is in proper 15 position to support the patient at his hips. Depending upon the character of the fracture or dislocation one or both feet of the patient are secured in the stirrups 26. The patient is thus supported in the frame of this invention both at his 20 hips and feet. It will be noted that the supporting 25 of the patient in the operating frame has been accomplished without the necessity of lifting the patient from the stretcher onto the operating table as is now common practice. The stretcher cart may now be removed from under the lower 25 extremities of the patient and the patient may rest his head and shoulders on the stretcher cart.

The lower extremities of the patient are thus rendered accessible for X-ray apparatus or fluoroscopic examination of the injured parts. 30 Exact mechanical traction may be applied to displaced or overriding fractures by proper manipulation of the stirrups 26. The lower extremities of the patient are fully accessible for the application of plaster casings, molded plaster splints, 35 or plaster casts, for the retention of the reduced deformity. After the operation is completed the stretcher cart is again placed in position to support the full length of the patient, the stirrups are removed from his feet, and the sacral rest is removed from under his thighs by manipulation 40 of hand wheels 19 and 25. A lifting of the patient from an operating table to the stretcher is thus made unnecessary.

While the above description of the use of the 45 frame of this invention has particular reference to the reduction and manipulation of fractures and dislocations of the lower extremities, it will be obvious to anyone skilled in the art that the frame may be used in very similar manner for 50 fractures or dislocations of the upper extremities, the stirrups in such instances being used for holding the patient's hands, and the sacral rests 55 16 being used to support the patient's shoulders.

I have described what I believe to be the best 55 embodiments of my invention. I do not, however, wish to be confined to the embodiments shown, but what I desire to cover by Letters Patent 60 is set forth in the appended claims.

I claim:

1. In combination, a sacral rest, extremity supporting members and means whereby said rest and members are supported in desired position with reference to each other, said means comprising a frame, means for supporting said members on said frame, said frame comprising a portion extending over said sacral rest, and means for supporting said sacral rest from said portion, said means comprising a perineal bar extending upwardly from said rest and carried by said portion.

2. In combination, a sacral rest, extremity supporting members and means whereby said rest and members are supported in adjustable position with reference to each other, said means

comprising a frame, means for supporting said members on said frame, said frame comprising a portion extending over said sacral rest, and a perineal bar extending upwardly from said rest and carried by said portion for supporting said sacral rest from said portion.

5. In combination, a sacral rest, extremity supporting members and means whereby said rest and members are supported in adjustable position with reference to each other, said means comprising a frame, means for supporting said members on said frame, said frame comprising a track extending over said sacral rest, a carriage on said track and a perineal bar extending vertically from said rest and supported from said carriage for supporting said rest from said carriage.

6. In combination, a sacral rest, extremity supporting members and means whereby said rest and members are supported in adjustable position with reference to each other, said means comprising a frame, means for supporting said members on said frame, said frame comprising a track extending over said sacral rest, a carriage on said track and a perineal bar extending vertically from said rest and supported from the carriage for supporting said rest from said carriage and means for adjusting the distance of said rest from said carriage.

7. In combination, a sacral rest, extremity supporting members and means whereby said rest and members are supported in adjustable position with reference to each other, said means comprising a frame, means for supporting said members on said frame, said frame comprising a track extending over said sacral rest, a carriage on said track and a perineal bar extending vertically from said rest and supported from the carriage for supporting said sacral rest from said carriage and means for propelling the carriage along said track.

8. In combination, a sacral rest, extremity supporting members and means whereby said rest and members are supported in desired position with reference to each other, said means comprising a frame, means for supporting said members on said frame, said frame comprising a portion, extending over said sacral rest, and means for supporting said sacral rest from said portion, said means comprising a perineal bar extending upwardly from said rest and supported from said portion and means for propelling said extremity supporting members with reference to said rest.

9. In combination, a sacral rest, extremity supporting members and means whereby said rest and members are supported in adjustable position with reference to each other, said means comprising a frame, means for supporting said members on said frame, said frame comprising a portion extending over said sacral rest, a perineal bar extending upwardly from said rest and supported from said portion for supporting said sacral rest from said portion, means for adjusting the distance of said rest from said portion, and means for propelling said extremity supporting members with reference to said rest.

10. In combination, a sacral rest, extremity supporting members and means whereby said rest and members are supported in adjustable position with reference to each other, said means comprising a frame, means for supporting said

members on said frame, said frame comprising a track extending over said sacral rest, a carriage on said track, a perineal bar extending vertically from said rest and supported by said carriage for supporting said rest from said carriage, means for propelling the carriage on said track, and means for propelling said extremity supporting members with reference to said rest.

11. In combination, a sacral rest, extremity supporting members and means whereby said rest and members are supported in adjustable position with reference to each other, said means comprising a frame, means for supporting said members on said frame, said frame comprising a track extending over said sacral rest, a carriage on said track and a perineal bar extending vertically from said rest and supported by said carriage for supporting said rest from said carriage means for adjusting the distance of said rest from said carriage, and means for propelling said extremity supporting members with reference to said rest.

12. In combination, a sacral rest, extremity supporting members and means whereby said rest and members are supported in adjustable position with reference to each other, said means comprising a frame, means for supporting said members on said frame, said frame comprising a track extending over said sacral rest, a carriage on said track and a perineal bar extending vertically from said rest and supported by said carriage for supporting said sacral rest from said carriage means for propelling the carriage along said track and means for propelling said extremity supporting members with reference to said rest.

13. In combination, a sacral rest, extremity supporting members and means whereby said rest and members are supported in adjustable position with reference to each other, said means comprising a frame, means for supporting said members on said frame, said frame comprising a track extending over said sacral rest, a carriage on said track and a perineal bar extending vertically from said rest and supported by said carriage for supporting said rest from said carriage, means for propelling the carriage along said track means for adjusting the distance of said rest from said carriage and means for propelling said extremity supporting members with reference to said rest.

14. In combination, a sacral rest, extremity supporting members and means whereby said rest and members are supported in adjustable position with reference to each other, said means comprising a frame, means for supporting said members on said frame, said frame comprising a track extending over said sacral rest, a carriage on said track, guide members for holding said carriage on said track, a perineal bar extending vertically from said rest and supported by said carriage for supporting said rest from said carriage, guide members for restraining said perineal bar to movements in the direction of its length with reference to said carriage, means for propelling the carriage along said track, means for adjusting the distance of said rest from said carriage and means for propelling the extremity supporting members with reference to said rest.

HERBERT M. BERGAMINI.
